HAIR DRYING AND SCALP TREATING
ARTICLE

Ann Morten, Seattle, Wash.

Application October 24, 1945, Serial No. 624,136

1 Claim. (Cl. 219—46)

1

This invention relates to improved means, for home or beauty parlor use, for the drying of the hair or for use in the treatment of the hair or scalp by the application of heat.

The invention has reference more particularly to a means of that character adapted to be wrapped about the user's head after the fashion of a scarf or turban, and is equipped with means whereby it may be heated electrically as required to obtain the hair drying or scalp treating effect.

It is the principal object of this invention to provide an article of the character and for the purposes above stated that may be easily and readily applied about the user's head, which may be easily and conveniently secured in place, and wherein an electric heating pad of a flexible, conformable character is embodied to furnish the hair drying or scalp treating heat.

It is also an object of this invention to provide a hair drying and treating means of the electrically heated type above stated, but which does not interfere with the user's moving about while the article is being used.

It is also an object of this invention to provide an article comprising a washable cover from which the heating pad may be easily removed in order that the cover may be washed.

Other objects of the invention reside in the details of construction and combination of parts, and in the mode of use of the article, as will hereinafter be fully explained.

In accomplishing these and other objects of the invention, I have provided the improved details of construction, the preferred design of which is illustrated in the accompanying drawings, where-

in—

Fig. 1 is a view of the present hair drying and treating means embodying the objects and advantages of the present invention.

Fig. 2 is a cross section of the same, taken on the line 2—2 in Fig. 1.

Fig. 3 is a view illustrating the mode of application and use of the present article for hair drying or scalp treating.

Referring more in detail to the drawings—

The present article is in the nature of an electric heating pad and is of such dimensions as to be convenient in use.

For convenience in application and use of the heating pad, which is designated in its entirety by reference character 10, the pad is contained within a fabric cover member 11. A flexible, protected cord, designated at 12, containing electric circuit wires, extends to the heating pad, and it is the intent that current be supplied through

2

a switch 15 of that character whereby more or less elements contained in the pad may be cut into or from the circuit, thus to supply more or less heat as required or desired. A present-day type of three-heat switch is preferred.

Furthermore, it is intended that the circuit connections shall be made through a plug and socket fitting, as at 14, so that the cord may be disconnected without requiring that the article be removed from the user's head.

The cover member 11 is in the nature of an elongated bag, closed at its longitudinal edges and at one end. The heating pad may be removed through the open opposite end, and when the pad is in place, this open end may be closed and secured by one or more buttons, as indicated at 16, or by other suitable means.

Secured to the cover, along one longitudinal edge of the bag, is a tie or ribbon 17, the ends of which extend beyond the ends of the bag. Formed along the other longitudinal edge of the cover is a hem in which a cord or draw string 18 is contained. The cover may be made of any suitable fabric, and preferably this would be of a washable character.

In using the device for drying the hair or for treating the hair or scalp, it is applied about the head after the fashion of a turban, preferably by placing the medial portion of the lower edge of 30 the cover across the forehead and extending the ends about the head in opposite directions and bringing the tie members into position that they may be tied together, either at the back or at the front of the head. Then the draw string is drawn up so as to gather the upper edge portion over 35 the head, leaving a small outlet for the escape of steam or moist air incident to the drying operation.

When the circuit is closed, the pad will become 40 heated and the degree of heat may be controlled as determined by the setting of the switch. After the pad has become heated, the circuit connection may be disconnected at 14 and the user may move freely about. If the drying operation is to 45 be continued, the circuit connections may be re-established at intervals.

Articles of this character are relatively inexpensive. They can be conveniently applied and can be made to conform to any size head, or accommodate any requirement for the drying of hair or treating of the scalp. The provision of 50 a drawstring enables the user to gather the cover portion about the top of the head to any extent required or desired.

55 One of the chief advantages of this article is

that the user is not required to remain seated in a chair during a prolonged drying or treating operation, but may by disconnecting the cord, have freedom of movement to carry on regular activities.

Such articles may be made in various sizes and of various materials, and the pad may be easily removed from the cover member when it is desired that the cover be cleaned or washed.

Such articles are especially useful in homes, but are also useful in beauty parlors or hair treating establishments.

Having thus described my invention, what I claim as new therein and desire to secure by Letter Patent is—

An article of the character described comprising a flexible, elongated fabric casing of bag-like form, and an elongated, electrically heated pad of flexible conformable character of substantially the same length as the casing contained therein; said pad and casing being adapted to be wrapped about the head after the fashion of a turban and having a tie strip secured along the

lower longitudinal edge with ends extended to tie the article about the head, and having a draw string applied in its other longitudinal edge to gather the same in about the head.

ANN MORTEN.
